UNITED STATES PATENT OFFICE.

ARTHUR E. FOWLE, OF TOLEDO, OHIO, ASSIGNOR TO THE LIBBEY-OWENS SHEET GLASS COMPANY, OF TOLEDO, OHIO, A CORPORATION OF OHIO.

SHEET-GLASS-DRAWING APPARATUS.

Application filed December 18, 1920. Serial No. 431,534.

To all whom it may concern:

Be it known that I, ARTHUR E. FOWLE, a citizen of the United States, residing at Toledo, in the county of Lucas and State of Ohio, have invented new and useful Improvements in Sheet-Glass-Drawing Apparatus, of which the following is a specification.

This invention is an improvement in the art of drawing sheet glass from a bath of molten glass, and relates especially to a simple and practical apparatus for maintaining the width of the sheet at or near the drawing point, before the sheet has set or assumed a non-plastic form.

One of the main difficulties to be overcome when sheet glass is drawn upwardly from a molten mass of glass, is the tendency of the sheet to narrow, or draw in at the edges, which will continue, if neglected, until the sheet pulls apart. Some means must be employed to hold the sheet to a constant and uniform width. Experience has shown that this may be accomplished by cooling the edge portions of the sheet as drawn, and adding an extra resistance or drag to the drawing of these edge portions to keep them tightly stretched at the sides of the sheet. In prior apparatus this end has been attained by using slowly rotating rollers above the source of the sheet edges, which feed up and from the edge portions of the sheet, at the same time cooling and holding back on these edges. The present invention aims to accomplish the same result, in a simpler manner, by localized cooling apparatus embodied in the opposite sides of the pot or receptacle containing the molten glass from which the sheet is drawn. This form of pot will form definite areas of cool stiff glass at those points from which the sheet edges are formed, and the greater resistance offered to the drawing force by this cooler glass will furnish the necessary drag at the sheet edges.

The invention will be better understood from the following drawings and detailed description of an apparatus for carrying into practice this invention.

In the accompanying drawings:

Fig. 1 is a vertical transverse section through the sheet drawing apparatus taken substantially in the plane of the drawn sheet, the sheet and water feeding pipes being shown in elevation.

Fig. 2 is a partial plan view of the mechanism, the sheet being in section on the line 2-2 of Fig. 1. In both views the apparatus is broken away at its center, the full width of the sheet being greater than shown ⁶⁰ in the drawings.

The sheet 1 is drawn upwardly from the molten bath of glass 2, in the receptacle or pot 3, and, in the form of apparatus indicated in the drawings, is bent laterally over ⁶⁵ a bending device 4, and carried off horizontally through any appropriate form of drawing mechanism and leer. The pot is enclosed by a suitable heating chamber, portions of which are indicated at 5. The ⁷⁰ mechanism and devices for drawing the sheet and maintaining the proper temperatures at various points have been omitted from the drawings for the sake of clearness. These parts of the apparatus may be of any ⁷⁵ suitable type.

The drawing pot or receptacle is made of refractory material and is of the well-known shallow form indicated in the drawings, having enclosing walls on three of the ⁸⁰ vertical sides, the fourth side, (at the bottom in Fig. 2), being open to communicate with the continuous tank furnace which supplies the molten glass. At the two opposite sides 6 and 7, the pot is formed with inwardly extending tapered vertical projections 8 and 9, the terminating edges ⁸⁵ 10 of which lie in the vertical plane of the glass sheet 1. On the outer sides of the pot walls 6 and 7, opposite the projections 8 and 9, are ⁹⁰ vertical reinforcing ribs or enlargements 11, and in the walls between the ribs and projections, are formed recesses 12 to accommodate the artificial cooling means.

These cooling devices, as here shown, are ⁹⁵ metallic castings 13, shaped to fit the recesses or pockets 12 in the wall of the pot, and having triangular inner sides to extend out into the projections 8 and 9 as indicated in Fig. 2. Each casing 13 is divided into two communicating compartments 14 and 15 by a partition 16, extending down from the top wall nearly to the bottom wall. An intake pipe 17 connects with the upper end of chamber 15 and an ¹⁰⁰ outlet pipe 18 connects with the upper end of chamber 14. Cold water or other fluid flows in through pipe 17, down through chamber 15 and up through chamber 14, as indicated by the arrows, and out through ¹⁰⁵ 110

the pipe 18. This circulation of cooling fluid serves to maintain the adjacent walls of the pot, and particularly the inner projections 8 and 9, at a much lower temperature than the surrounding portions. These cooled projections will cause localized areas of substantially cooler glass to be formed in the molten bath 2, adjacent these projections. These cooler areas form the sources for the sheet edge portions, and it will require a much greater pulling strain to draw the edges from these comparatively cold area than from the warmer and less viscous glass in the remainder of the pot. This added resistance serves to stretch taut the cooler edge portions of the sheet and keep the sheet to the required width.

Applicant is aware that previous patents have contemplated drawing the sheet edges from sources which are cooler than the source from which the central portions of the sheet is drawn. However, the form of pot here shown with self-containing cooling devices for forming definitely localized areas of cooler glass, as sources for sheet edge portions, is believed to be new. The particular form of cooling device illustrated is shown merely by way of example, any other equivalent device, contained within the walls of the pot out of contact with the molten glass, being contemplated as falling within the scope of this invention.

Claims:

1. In an apparatus for producing sheet glass, wherein a sheet is drawn upward from a mass of molten glass, a pot containing the bath of molten glass, said pot having projections extending inwardly from the side walls adjacent the sources of the sheet edges, and cooling means within the pot walls and out of contact with the molten glass for maintaining the projections at a lower temperature than the other portions of the pot.
2. In an apparatus for producing sheet glass, wherein a glass sheet is drawn upward from a mass of molten glass, a pot containing the mass of molten glass, said pot having tapered vertical projections extending inwardly from the side walls adjacent the sources of the sheet edge portions, and cooling means within the pot walls for maintaining these projections at a lower temperature than the other portions of the pot.
3. In a sheet glass drawing apparatus, a pot containing a bath of molten glass, and means for drawing the glass sheet upwardly therefrom, the pot having opposed inward projections on the two sides adjacent the sources of the sheet edges, there being pockets in the pot walls behind the projections,

the pockets being open at the top above the glass level, and the molten glass having no access thereto, and fluid cooling means in the pockets for lowering the temperature of the projections.

4. In a sheet glass drawing apparatus wherein a sheet of glass is drawn upwardly from a mass of molten glass, a pot containing the mass of molten glass, having inwardly extending projections on the two opposite vertical side walls adjacent the sources of the edges of the sheet, and recesses or pockets within the walls behind these projections, the pockets being open at the top above the glass level, and the molten glass having no access thereto, and casings fitting within these recesses within which a cooling fluid circulates.

5. In an apparatus for producing sheet glass, wherein a sheet of glass is drawn upward from a mass of molten glass, a pot containing the molten glass, said pot having enlargements in the opposite side walls comprising tapered inward projections extending out into the molten bath, there being vertical pockets with upper open ends formed in these enlargements, the inner sides of the pockets conforming with the tapered projections, and metallic cooling devices fitting within these pockets and each comprising a self-contained fluid cooling system.

6. In an apparatus for producing sheet glass, wherein a glass sheet is drawn upward from a mass of molten glass, a pot containing the mass of molten glass, said pot having tapered vertical projections extending inwardly from the side walls adjacent the sources of the sheet edge portions said projections extending throughout the entire depth of the pot.

7. In an apparatus for producing sheet glass, wherein a glass sheet is drawn upwardly from a mass of molten glass, a pot containing the mass of molten glass, said pot having pointed vertical projections extending inwardly from the side walls and adjacent the source of the sheet edge portions.

8. In an apparatus for producing sheet glass, wherein a glass sheet is drawn upwardly from a mass of molten glass, a pot containing the mass of molten glass, said pot having pointed vertical projections extending inwardly from the side walls and adjacent the source of the sheet edge portions, said projections extending throughout the entire depth of the pot.

Signed at Toledo, in the county of Lucas and State of Ohio, this 16th day of Dec., 1920.

ARTHUR E. FOWLE.
